Inventor:
Paul R. Fortin,

by Alexander S. Zunt,
His Attorney.

UNITED STATES PATENT OFFICE.

PAUL R. FORTIN, OF SCHENECTADY, NEW YORK, ASSIGNOR TO GENERAL ELECTRIC COMPANY, A CORPORATION OF NEW YORK.

ELECTRIC CONDENSER.

Application filed May 13, 1925. Serial No. 30,072.

My invention relates to electric condensers, particularly to high voltage power air condensers, and an object of my invention is to provide an improved condenser of this type which for a given capacity and voltage shall be compact and shall not be subject to corona loss.

My invention will be better understood from the following description taken in connection with the accompanying drawing, and its scope will be pointed out in the appended claims.

In the drawing, Fig. 1 is a side elevation of a complete condenser involving my invention; Fig. 2 is a perspective view of a single element or plate of the condenser shown in Fig. 1; Fig. 3 is a detail of the plate shown in Fig. 2; Fig. 4 is a fragmentary view showing a condenser similar to that illustrated by Fig. 1 but having an adjustable upper plate; Fig. 5 is a top plan of the condenser shown in Fig. 4; Fig. 6 is a cross section of the adjustable plate of Fig. 4; and Fig. 7 is a detail of the adjusting means.

Referring to the drawing, the supporting frame of the condenser comprises upper and lower frame members 1 and 2 connected by struts 3 to which the condenser plates are secured. Each of the fixed plates 4 is shown circular in shape and comprises an external metallic ring 5 and two sheet metal disks 6 and 7. The outer surface 8 of the ring 5 has a rounded contour which in cross-section is preferably the arc of a circle and on opposite sides of the ring are annular grooves 9 and 10. The two disks 6 and 7 are somewhat dished and have their edges beveled to fit the grooves 9 and 10. By virtue of their being dished the disks may be sprung into the grooves in the ring 5 and will be firmly held therein by reason of their natural resiliency. Additional security may be obtained by rolling the edge of the ring over the edge of the disk. The plates thus formed are equally spaced at all points and each has an effective thickness equal to the diameter of the rounded edge formed by the ring 5. The curvature of this edge and the spacing of the plates, which may be relatively small, are such that with the potential differences employed the gaps between the plates function substantially like sphere gaps giving to the condenser the break-down characteristic of a sphere gap

so that corona does not precede sparkover. By forming the grooves 9 and 10 well in from the rounded outer edge of the ring 5, any unavoidable slight roughness at the junction of the ring and the disks is sufficiently far from the curved edge that it does not start an arc-over at this point.

Each condenser plate is shown provided with three equidistant radial supporting arms 12 which by means of J-bolts 13 are secured to the struts 3, alternate plates having their arms secured to the same struts as will be apparent from Fig. 1. By loosening the J-bolts 13, the spacing of the plates relative to each other may be readily changed. Where a small adjustment of the capacitance of the condenser is desired, the uppermost plate may be constructed and mounted, as shown in Figs. 5, 6 and 7. In that case the adjustable plate 15 is made similar to the fixed plates 4, except that instead of having external supporting arms it is provided with the internal spider 16 to which the threaded rod 17 is secured through a hub 18. The bushing 19 surrounds the rod 17 where it passes through the top member of the frame and between the bushing and a strap 20 is a nut 21 having an enlarged grooved portion 22 for receiving a belt 23. The pin 24 carried by the rod 17 rides in a longitudinal slot in the bushing 19 and prevents turning of the rod.

While I have described only one embodiment of my invention, I do not wish to be limited to the particular form shown and described, as it will be apparent that many modifications therein may be made without departing from the scope of my invention as set forth in the appended claims.

What I claim as new and desire to secure by Letters Patent of the United States is:—

1. A condenser plate comprising a ring having a rounded outer surface and a disk secured to and bounded by said ring.
2. A condenser plate comprising a ring having a rounded outer surface, and a pair of spaced plates secured at their peripheral portions to opposite sides of said ring.
3. A condenser plate comprising a ring having a rounded outer surface and a pair of spaced dished disks, said disks being in resilient engagement with said ring at opposite sides thereof.
4. A condenser plate comprising a ring having grooves on opposite faces thereof, and

a pair of resilient spaced plates, each of said plates being dished and being sprung into one of said grooves.

5. A condenser comprising a series of 5 plates in electrostatic relation with each other, adjacent plates being uniformly spaced throughout their extent and each having a rounded peripheral portion of approximately the same thickness as the 10 plates.

6. A condenser comprising a plurality of plates, each having an edge portion substantially semi-circular in cross-section and having an effective thickness substantially equal

to the diameter of the edge portion and 15 means for supporting said plates from their edge portions in spaced relation.

7. In a variable air condenser an adjustable plate comprising a ring, a pair of spaced disks engaging said ring at opposite 20 sides thereof, means arranged between the disks and secured to the ring, and means engaging said means between the disks near the center thereof for moving the plate.

In witness whereof, I have hereunto set 25 my hand this 11th day of May, 1925.

PAUL R. FORTIN.
